B. Singr. Atg.

UNITED STATES PATENT OFFICE.

STEFAN STEINMETZ, OF BERLIN, GERMANY.

METHOD OF GRINDING.

Application filed August 28, 1921. Serial No. 495,528.

To all whom it may concern:

Be it known that I, STEFAN STEINMETZ, a citizen of the German Republic, and a resident of Berlin, Germany, have invented a certain new and useful Improved Method of Grinding (for which I have obtained a patent in Germany, No. 311,271, October 11, 1917), of which the following is a specification.

10 The difficulty of breaking up bran into very fine pieces in a mechanical way and with known grinding devices lies in the property of the bran to offer, if to be converted into a very fine powder, a resistance 15 which is the greater the more the state of the bran during the reduction approaches the "flour-free state." The cause for this phenomenon resides in the bran assuming gradually the form of thin and curved 20 lamellæ which easily slip through the grinding path in general and the grinding furrows in particular.

The invention is based upon the cognizance that two features promote the transformation of bran into powder, viz:

1. The grinding process must be such that, first, the bran remains preserved in the form of as large scales as possible, because in this case the coarseness of the flour produced 30 from the bran remains tangible and the starch- and gluten-cells are protected from destruction impairing their germinating power.

2. When the bran has been obtained in this known manner, it is converted into a very fine powder by two separate mechanical steps consisting in the bran being first cut to pieces and then ground down. This may, if desired or necessary, be continued 40 until the bran has attained a degree of fineness which is even greater than that of the core flour already obtained.

This manner of operation is preferably carried through by means of disk-mills, the disks of which rotate in opposite directions. The grinding disks should be covered with pieces of hard cast iron or another suitable material and said pieces should have furrows or ripples provided with sharp, blade-like teeth adapted to act like scissors and to cut the bran to pieces. The sifting after the cutting must be so fine already that only the by far smallest particles pass through.

The remaining particles are preferably introduced into another mill of the same kind, 55 but having the disks covered with emery, or with plates of tangible coarseness, by which the pre-worked bran is completely ground down. The two mills may be combined to one. Sifting the product after the two 60 working phases mentioned is preferably effected by air currents carrying away only the finest particles of the bran, but instead of this means adequately fine sieves may be made use of. The fineness of the grinding 65 down, controlled by the fine sifting, warrants extracting the nutrients still contained in the bran, as well as their digestibility.

In order to make my invention more 70 clear, I refer to the accompanying drawing which explains rather diagrammatically the transformation of bran into bran dust by means of a disk mill having a double disintegrating surface. Figure 1 is a vertical 75 transverse section through the mill and shows chiefly a plan of one of the grinding disks; Figure 2 is a vertical longitudinal section through this mill.

After the grain has been freed, preferably 80 on the wet way, from its outer strawy skin and the flour core has been extracted by the ordinary grinding procedure, the bran remaining from this procedure is introduced through the hopper 1 into the mill, the disks 85 2 and 3 of which rotate in opposite directions and are covered with concentric grinding rings 4, 6 and 5, 7. The rings 4 and 5 are rippled and work together like a pair of scissors so that they actually cut the bran. 90 The grinding rings 6 and 7, however, which consist of emery or an equivalent material reduce the cut bran particles to dust which then is conducted to a pneumatic sifter 8 or to a sifting machine having adequately fine 95 sieves.

The remainders are re-conducted into the mill through the passage 9 where they are treated a second time, and this is, or may be, repeated until the bran has, so to say, been ground dead. The other portion of the 100 dust is retained after each sifting and the whole, or, may be, solely its nutritious components separated from it by sifting, are, finally added to the flour intended for the 105 baking.

Having now described my invention, what

I desire to secure by a patent of the United States is:

The process of obtaining the nourishing particles in bran, consisting in first separating the bran from the grain in the form of scales or lamellas, secondly cutting these scales or lamellas to bring them into a form other than scales or lamellas, and thereafter

grinding the cut lamellas or scales to most finely divided powder.

In testimony whereof I affix my signature in presence of two witnesses.

10 STEFAN STEINMETZ.

Witnesses:

OTTO T. BRUNN,
PAUL BRABAND.
